US00D631832S

(12) **United States Design Patent**
Onnerud et al.

(10) **Patent No.:** **US D631,832 S**
(45) **Date of Patent:** ** *Feb. 1, 2011

(54) **BATTERY PACK**

(75) Inventors: **Per Onnerud**, Framingham, MA (US);
Christina M. Lampe-Onnerud,
Framingham, MA (US); **Wilmont E. Howard**, Silver Spring, MD (US)

(73) Assignee: **Boston-Power, Inc.**, Westborough, MA (US)

(*) Notice: This patent is subject to a terminal disclaimer.

(**) Term: **14 Years**

(21) Appl. No.: **29/312,312**

(22) Filed: **Oct. 14, 2008**

(51) LOC (9) Cl. **13-02**

(52) U.S. Cl. **D13/103**

(58) Field of Classification Search D13/102-106,
D13/110, 118-119, 184; 429/96-100, 163,
429/176

See application file for complete search history.

(57) **CLAIM**

The ornamental design for a battery pack, as shown and described.

DESCRIPTION

FIG. 1 is a perspective view of a battery pack showing our new design.

FIG. 2 is a top plan view of FIG. 1, with the bottom plan view being identical.

FIG. 3 is a side elevational view of FIG. 1, with the other side view being identical; and,

FIG. 4 is a front elevational view of FIG. 1, with the rear view being identical.

The article is a battery pack. The battery pack is a combination of individual batteries arranged as shown. The claim is directed to the collective appearance of the individual batteries in the combination shown.
